Primary Examiner — Rhea Shields

(57) **CLAIM**

The ornamental design for a hearing aid charging unit, as shown and described.

DESCRIPTION

1. Hearing aid charging unit

1.1 : Front

1.2 : Back

1.3 : Right

1.4 : Left

1.5 : Bottom

1.6 : Top

1.7 : Perspective

Fig. 1.1 is a front side view of a hearing aid charging unit showing our new design; fig. 1.2 is a rear side view thereof; fig. 1.3 is a right side view thereof; fig. 1.4 is a left side view thereof; fig. 1.5 is a bottom view thereof; fig. 1.6 is a top view thereof; fig. 1.7 is a top, front and left side perspective view thereof.

In the drawings, the broken lines are for the purpose of illustrating environment only and form no part of the claimed design.

1 Claim, 7 Drawing Sheets(56)
